UNITED STATES PATENT OFFICE.

ORVILLE E. SWICK, OF WESTON, WEST VIRGINIA.

POOL-TABLE ATTACHMENT.

1,114,202.

Specification of Letters Patent.

Patented Oct. 20, 1914.

Application filed January 29, 1914. Serial No. 815,304.

To all whom it may concern:

Be it known that I, ORVILLE E. Swick, a citizen of the United States, residing at Weston, in the county of Lewis and State of West Virginia, have invented a new and useful Pool-Table Attachment, of which the following is a specification.

The present invention relates to improvements in pool table attachments, one object 10 of the invention, being the provision of a novel form of shutter and actuating mechanism for the ball collecting tray generally used with the automatic structure for receiving the balls from the pockets and delivering the same to one end of the table, 15 where all balls may be accumulated and finally recovered for placement in the triangle.

A further object of the invention is the 20 provision of a novel mounting of the shutter, whereby the same is protected in its extreme movement to prevent the breakage of the connection thereof to its operating mechanism and also to relieve any sudden jar 25 placed upon the spring which automatically returns the shutter to closed position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 35 within the scope of what is claimed without departing from the spirit of the invention.

In the drawings—Figure 1 is a top plan view of a tray constructed according to and embodying the present invention. Fig. 2 is a 40 bottom plan view thereof. Fig. 3 is a section taken on line 3—3 of Fig. 2. Fig. 4 is a section taken on line 4—4 of Fig. 2. Fig. 5 shows a perspective view of the end of a pool table with the rack attached thereto.

Referring to the drawings, the numeral 1 45 designates the tray, which is adapted to be supported, as is usual, at one end of the table below the same and between the supporting legs thereof so that the inlet portion 50 2 will be in a position to receive the ball from the raceways led from the pockets, the receptacle 3 being formed in the tray as indicated in Fig. 1 so as to accommodate the various balls as the same are delivered from 55 the pockets. The outlet 4 is provided at the extreme end of the circuituous channel 3

and is controlled by means of the automatically closed shutter 5. This shutter 5, as clearly shown in Figs. 2 and 3, has oppositely disposed wings or tongues 6, which 60 slide in the grooves 7 formed in the walls 8 of the transversely disposed slots formed in the under side of the tray 1 and as particularly shown in Fig. 2. By this means the shutter is adapted to slide to assume the full 65 and dotted line positions in Fig. 2, so that the opening 4 may be closed and opened to thus retain the balls within the receptacle 3 or permit the release of one at a time thereof through the opening 4. 70

Connected to the under side of the shutter 5 as clearly illustrated in Figs. 2 and 3, is a triangular shaped plate 8', which is secured at its three corners by means of screws 9 to the under side of the shutter 5 75 and has struck therefrom so as to stand at right angles thereto, the triangular apertured lug 10. Mounted through the apertured lug 10 is one end of the operating rod 11, which is prevented too far outward 80 displacement and also connected so that the shutter may be moved from the full to dotted line position when the rod 11 is pulled upon by means of the nut 12. This rod 11 also extends through the apertured lug 13 85 of the open plate 14, whose inner end is connected by means of four screws 15 to the under side of the tray 1 at the forward edge thereof, said plate 14 being further provided with the alined apertured lug 16 90 through which the rod 11 is adapted to slide. Thus the rod 11 is insured a straight line movement when the hooked terminal 17 is pulled upon by means of any mechanism that is usually employed for manually opening the shutter 5. A spring 18 is disposed upon the rod 11 between the lugs 10 and 13, 95 so that when the rod and parts are pulled to assume the dotted line position in Fig. 2, the spring will be placed under compression, 100 to automatically return the shutter 5 to closed position. In order to limit the movement of the rod 11 and consequently the shutter 5 and to relieve the strain thrown upon the shutter that would tend to break 105 the same when released to the action of the spring or pulled upon too suddenly and moved too far by the manual actuation of the rod 11, a pin 19 is connected to the rod 11 between the lugs 13 and 16, said lugs co- 110 acting with the pin to limit the movements of the rod 11 and to receive any jar placed

thereupon. By this means, the strain is placed upon the pin 19 and lugs 13 and 16 and not upon the connection of the rod to the shutter 5, thus making the present device more durable than the devices now in use and at the same time preventing the present structure from being easily placed out of commission or use by rough usage.

What is claimed is:

10. 1. A pool table attachment, including a ball tray having an outlet, a shutter for controlling said outlet, a rod connected to the shutter for operating the same, a spring for closing the shutter, a plate having two up-standing and spaced lugs attached to the tray and through which the rod slides, and an abutment carried by the rod for coaction with one lug at a time for limiting the movement of the rod and for relieving the jar upon the shutter during the closing thereof.
15. 2. A pool table attachment, including a ball tray having an outlet, said tray being provided with a slot disposed adjacent to the outlet, a shutter mounted for sliding movement in the slot and for controlling

the outlet, a metal plate connected to the under side of the shutter, an apertured lug carried by the plate, a second plate connected to the tray and provided with two apertured and spaced lugs, the apertures of all of the lugs alining, a rod disposed in the apertures of all lugs, whereby the rod is guided in the two lugs of the last plate and is secured to the shutter through the remaining lug, a spring disposed upon the rod and abutting the lug of the first plate and one of the lugs of the second plate, said spring exerting a tension to close the shutter, and a projection carried by the rod between the two spaced lugs for limiting the movement of the rod during the opening and closing of the shutter.

In testimony that I claim the foregoing as my own, I have hereto affixed my signature in the presence of two witnesses.

ORVILLE E. SWICK.
